UNITED STATES PATENT OFFICE.

DOCTOR FRANKLIN MORGAN, OF CHICAGO, ILLINOIS.

DESIGN FOR A VALVE-CASING FOR RADIATORS.

SPECIFICATION forming part of Design No. 35,301, dated November 19, 1901.

Application filed October 7, 1901. Serial No. 77,918. Term of patent 14 years.

To all whom it may concern:

Be it known that I, DOCTOR FRANKLIN MORGAN, a citizen of the United States, residing at Chicago, in the county of Cook and State 5 of Illinois, have invented and produced a new and original Design for a Valve-Casing for Radiators, of which the following is a specification, reference being had to the accompanying drawings, forming a part hereof.

Figure 1 is a side elevation of a valve for radiators embodying my new design. Fig. 2 is a rear elevation of such valve; and Fig. 3 a front elevation thereof, all of such figures being necessary to illustrate the same.

A reference-letter applied to designate a given part is used to indicate such part throughout the several figures of the drawings wherever the same appears.

As shown in the drawings, the leading or 20 material features of my design consist of the

cylindrical barrel A, provided about midway of the length thereof with the projection B, such projection B having the semispherical part b and the screw-threaded part b' and the flanged part b".

The cylindrical barrel A is provided with dome-shaped top a' and with the bottom a".

Having thus described my invention, what I claim as new, and desire to secure by Letters Patent, is—

The design for a valve-casing for radiators as shown and described.

In testimony whereof I have signed my name to this specification in the presence of two subscribing witnesses.

DOCTOR FRANKLIN MORGAN.

Witnesses:

CHARLES TURNER BROWN,
CORA A. ADAMS.
